UNITED STATES PATENT OFFICE

ALONZO ALDRICH, OF BELOIT, WISCONSIN

FOURDRINIER PAPER MACHINE

Application filed July 5, 1923. Serial No. 649,455.

My invention relates to Fourdrinier paper making machines, and particularly, though not necessarily, to such as have a table made laterally removable to facilitate application 5 of a new wire.

One of the objects of the invention is to arrange for the advantageous mounting of the removable table and its breast roll relatively to the devices for holding and feeding the 10 paper pulp.

Another object of the invention is to arrange for the vertical adjustment of both the table with its breast roll and the paper material holding and feeding devices.

15 Another object of the invention is to secure easy and proper cooperation between all these parts.

Another object of the invention is to permit ready removal of the table and prevent 20 interference therewith even though the latter is mounted for cooperative adjustment of paper holding and feeding devices.

Other objects will appear and be pointed out hereinafter.

25 In the accompanying drawings, Fig. 1 is a side elevation of the feed end of a Fourdrinier machine and paper material holding and feeding devices embodying my present invention;

30 Fig. 2 is a cross section on line 2—2 in Fig. 1; and

Fig. 3 is an end elevation of the structure shown in Fig. 1.

Referring to the drawings, I show the end 35 of a table 1 having rolls 2 and a breast roll 3 and wire 3a thereon. The table is mounted for lateral removal for placing a new wire, and is accordingly shown with mechanism therefor. This comprises wheels 4 mounted

40 on power shaft 5 and arranged to travel on tracks 6 mounted on pedestals 6a on floor or foundation. But as this mechanism of itself forms no part of my present invention, being disclosed and claimed in Patent No.

45 1,421,752, issued July 4, 1922, to myself and A. L. Larson, it is not shown in full and will not be described further. The breast roll 3 is preferably mounted for adjustment longitudinally of the table, as by mounting it on 50 slides 7 adjusted by handle 8 through suit-

able gearing 9, 10 and 11, and rack 12. This adjusting mechanism of itself forms no part of my present invention, being shown, described and claimed in my Patent No. 1,494,567, issued May 20, 1924.

55

A feed box 13 and tank 14 for holding paper material and feeding same to wire 3a near or above breast roll 3 is provided. These are mounted on a supporting structure conveniently comprising side upright members 15—15 adapted to rest on floor or foundation 16 and cross connecting beams 17, 18 and 19 secured to said members 15 and cross member 20 between members 18 and 19. This frame or supporting structure fits between 60 posts 21—21 on floor or foundation 16, and is adapted to pivot on same about its forward end, for purposes to be explained later.

Arrangement is made for supporting table end by feed box supporting structure and also 70 connecting same together so that relation between same may be determined and maintained, and also so that they may be adjusted together. As a simple and practical arrangement, the ends of the breast roll slides 7 are 75 mounted on shoulders or abutments 23 on members 15, and screw bolts 24 with capstan nuts 25 are provided for detachably connecting or securing slides 7 to members 15, bolts 24 being preferably pivoted by pins 26 to 80 permit adjustment and movement out of way. Thus feed end of table with its breast roll and paper material holding and feeding devices are detachably secured or held together so as to maintain proper relationship and also 85 to permit joint adjustment of same. Also, table may be readily disconnected to permit its removal for applying new wire.

Arrangement is also made for the vertical adjustment of the paper material holding and 90 feeding devices and table end combined, so as to obtain inclination of wire for effect in arranging fibers on wire. While various lifting mechanisms could be used, as an advantageous arrangement and matter of further and specific improvement, I show a floating adjusting mechanism for raising and lowering the rear end of paper material devices supporting structure. The mechanism shown comprises floating frames 27 provided 95 100

with pointed bearings 28 resting on V-shaped supporters 29 on foundation 16. Frames 27 carry adjusting screws 30, arranged for vertical movement in sockets 31 on frames 27 and having their upper ends provided with caps 32 having pointed ends fitting into recesses in abutments in projections 34 on members 15. Adjusting screws 30 are raised and lowered by suitable power mechanism, as electric motor 36 geared to cross shaft 37 having worm and gear connections with screws 30, the worms on screws 30 having threaded sockets for screws 30 so that rotation of the worms will raise and lower the screws. Thus operation of motor 36 will cause rotation of adjusting worms on screws 30 and thereby cause raising and lowering of frame members 15 and with them the paper holding and feeding devices and feed end of table, and proper relationship of table and paper holding and feeding devices will be maintained constantly, irrespective of position in adjustment of same.

It will be understood that changes and modifications may be made without departing from the spirit of the invention.

What I claim is:

1. A Fourdrinier machine having an adjustable and removable table and adjustable paper material holding and feeding devices, and means for adjusting the table by adjusting the paper holding and feeding devices.

2. The combination with the table and paper material holding and feeding devices, of means for supporting all of the same, and mechanism for raising and lowering said supporting means, said mechanism being adapted to raise and lower the far end or said supporting means and thereby tilt supporting means and table, said raising and lowering means comprising elevating mechanism interposed between supporting means and foundation and adapted to rest on latter and push up on former, said mechanism comprising a floating support carrying a power generator and an adjustable member driven thereby.

3. The combination with the table and paper material holding and feeding devices, of means for supporting all of the same, and mechanism for raising and lowering said supporting means, said mechanism being adapted to raise and lower the far end of said supporting means and thereby tilt supporting means and table, said raising and lowering means comprising elevating mechanism interposed between supporting means and foundation and adapted to rest on latter and push up on former, said mechanism comprising a floating support carrying a power generator and an adjustable member driven thereby by worm and wheel driving connections.

4. The combination of a removable table and paper material holding and feeding de-

vices, of means for supporting both the table and said devices, the table having an adjustable breast roll carrying structure and means for supporting same on and connecting it to said supporting means.

5. In a Fourdrinier machine the combination of a laterally removable table and a supporting structure mounted on the floor, the breast roll end of the table being mounted on and supported by said structure, the table being provided with a longitudinally adjustable carriage for the breast roll and said carriage being provided with means arranged and adapted to make the connection between the table end and said supporting structure.

6. In a Fourdrinier machine the combination of a laterally removable table and a supporting structure mounted on the floor, the breast roll end of the table being mounted on and supported by said structure, the table being provided with a longitudinally adjustable carriage for the breast roll and said carriage being provided with means arranged and adapted to make the connection between the table end and said supporting structure, and means for detachably connecting said breast roll carriage to said supporting structure.

7. In a Fourdrinier machine the combination of a laterally removable table and a supporting structure mounted on the floor, the breast roll end of the table being mounted on and supported by said structure, the table being provided with a longitudinally adjustable carriage for the breast roll and said carriage being provided with means arranged and adapted to make the connection between the table end and said supporting structure, said supporting structure being provided with a supporting abutment and said breast roll carriage being adapted to rest upon said abutment.

8. In a Fourdrinier machine the combination of a laterally removable table and a supporting structure mounted on the floor, the breast roll end of the table being mounted on and supported by said structure, the table being provided with a longitudinally adjustable carriage for the breast roll and said carriage being provided with means arranged and adapted to make the connection between the table end and said supporting structure, said supporting structure being provided with a supporting abutment and said breast roll carriage being adapted to rest upon said abutment, and means for detachably connecting said breast roll carriage to said abutment.

9. In a Fourdrinier machine the combination of a supporting structure adapted to rest on the floor and having a horizontal abutment, a laterally removable table having a longitudinally adjustable breast roll carriage forming the breast roll end of the table, said

- breast roll carriage being adapted to be adjusted toward and away from said supporting structure so that the end of the carriage may come in position above the supporting structure abutment to permit the support of the breast roll end of the table, and said carriage being movable so as to withdraw its end from position over said abutment so as to permit the table to be adjusted for its lateral removal.
10. In a Fourdrinier machine the combination of a supporting structure adapted to rest on the floor and having a horizontal abutment, a laterally removable table having a longitudinally adjustable breast roll carriage forming the breast roll end of the table, said breast roll carriage being adapted to be adjusted toward and away from said supporting structure so that the end of the carriage may come in position above the supporting structure abutment to permit the support of the breast roll end of the table, and said carriage being movable so as to withdraw its end from position over said abutment so as to permit the table to be adjusted for its lateral removal, and means for detachably connecting the end of the breast roll carriage to said abutment.
11. In a Fourdrinier machine the combination of a supporting structure adapted to rest on the floor and having a horizontal abutment, a laterally removable table having a longitudinally adjustable breast roll carriage forming the breast roll end of the table, said breast roll carriage being adapted to be adjusted toward and away from said supporting structure so that the end of the carriage may come in position above the supporting structure abutment to permit the support of the breast roll end of the table, and said carriage being removable so as to withdraw its end from position over said abutment so as to permit the table to be adjusted for its lateral removal, and means for detachably connecting the end of the breast roll carriage to said abutment, said means comprising bolts on the structure and nuts engaging the breast roll carriage.
12. In a Fourdrinier machine the combination of a laterally removable table, a supporting structure on which the breast roll end of the table is mounted and pulp holding and feeding devices mounted on top of said supporting structure, and means for vertically adjusting the end of said supporting structure farthest from the table so as to tilt said structure and thereby adjust the table end and tilt the pulp holding and feeding devices.
13. In a Fourdrinier machine the combination of a laterally removable table, a supporting structure on which the breast roll end of the table is mounted and pulp holding and feeding devices mounted on top of said supporting structure, and means for vertically adjusting the end of said supporting struc-
- ture farthest from the table so as to tilt said structure and thereby adjust the table end and tilt the pulp holding and feeding devices, and means for detachably connecting the table end with said supporting structure, said means comprising pivoted bolts on the supporting structure and nuts on said bolts engaging the table end.
14. In a Fourdrinier machine the combination of a laterally removable table, a supporting structure on which the breast roll end of the table is mounted and pulp holding and feeding devices mounted on top of said supporting structure, and means for vertically adjusting the end of said supporting structure farthest from the table so as to tilt said structure and thereby adjust the table end and tilt the pulp holding and feeding devices, and means for detachably connecting the table end with said supporting structure, said means comprising pivoted bolts on the supporting structure and nuts on said bolts engaging the table end, and said supporting structure adjusting means comprising a floating carriage provided with vertically adjustable screw rods, the upper ends of which engage said supporting structure, worm wheels having threaded sockets in which said threaded rods are fitted, and a rotary shaft carrying worms engaging said worm wheels and means for driving said rotary shaft.
15. In a Fourdrinier machine the combination of a laterally removable table, a supporting structure adapted to rest on the floor and having means for supporting said table and means for vertically adjusting said supporting structure to tilt the same.
16. In a Fourdrinier machine the combination of a laterally removable table, a supporting structure adapted to rest on the floor and having means for supporting said table and means for vertically adjusting said supporting structure, and paper holding and feeding devices mounted on top of said supporting structure and having an outlet located over the wire near the breast roll.
17. The combination with a laterally removable table and feed box therefor, of a support by which the breast roll end of the table may be supported and with which it may be detachably connected, whereby the table may be laterally removed without moving said support, said support also serving as a support for the feed box, and means for vertically adjusting said support whereby said breast roll end of the table and said feed box will be vertically adjusted together to secure vertical inclination of the table.
18. A machine of the class specified having a laterally removable table and also having a tilting supporting frame at the feed end of said table.
19. A machine of the class specified having a laterally removable table and also hav-

ing a tilting supporting frame at the feed end of said table, and means for tilting said frame.

20. A machine of the class specified having a laterally removable table and also having a tilting supporting frame at the feed end of said table and a feed box mounted on said tilting frame so as to be inclined by the tilting action of the frame.

21. A machine of the class specified having a laterally removable table and also having a tilting supporting frame at the feed end of said table and a feed box mounted on said tilting frame so as to be inclined by the tilting action of the frame and means for tilting said frame.

22. A machine of the class specified having a laterally removable table and also having a tiltable supporting frame at the feed end of the table and means for detachably connecting said end of the table to said frame.

23. A machine of the class specified having a laterally removable table and also having a tiltable frame at the feed end of the table, said frame being provided with an abutment on which the feed end of the table may rest and means for detachably connecting the table end to said abutment.

24. A machine of the class specified having a detachable table and also having a tiltable frame at the feed end of the table, said frame being provided with an abutment on which the feed end of the table may rest and means for detachably connecting the table end to said abutment, and a feed box mounted on said tiltable frame and arranged to be inclined by the tilting action thereof.

25. A machine of the class specified having a detachable table and also having a tiltable frame at the feed end of the table, said frame being provided with an abutment on which the feed end of the table may rest, means for detachably connecting said end of the table to said abutment and means for adjusting the side of said frame opposite said abutment in a vertical manner so as to tilt said frame vertically.

26. A machine of the class specified having a detachable table and also having a tiltable frame at the feed end of the table, said frame being provided with an abutment on which the feed end of the table may rest, means for detachably connecting said end of the table to said abutment and means for adjusting the side of said frame opposite said abutment in a vertical manner so as to tilt said frame vertically, and a feed box mounted on said frame so as to be inclined by the tilting action of the frame.

27. A machine of the class specified having a laterally removable table and a supporting frame at the feed end of said table, said frame having an abutment on which the feed end of the table may rest.

28. A machine of the class specified having

a detachable table and a supporting frame at the feed end of said table, said frame having an abutment on which the feed end of the table may rest, and said table having a longitudinally movable breast roll carrying structure adapted for movement so that its outer end portion may be adjusted to position over said abutment.

29. A machine of the class specified having a detachable table and a supporting frame at the feed end of said table, said frame having an abutment on which the feed end of the table may rest, and said table having a longitudinally movable breast roll carrying structure adapted for movement so that its outer end portion may be adjusted to position over said abutment, and means for detachably connecting said breast roll carrying structure to said abutment.

30. A machine of the class specified having a laterally removable table and also having a feed box and a support therefor at the feed end of the table, said table having its feed end supported by said feed box support.

31. A machine of the class specified having a laterally removable table and also having a feed box and a vertically adjustable support for the feed box at the feed end of the table, said support and table being provided with cooperating devices whereby the feed end of the table is supported by said support, and detachably connected therewith and means for vertically adjusting said support.

32. A machine of the class specified having a laterally removable table and also having a feed box and a support for the feed box at the feed end of the table, said support and table being provided with cooperating devices whereby the feed end of the table may be detachably mounted on said support, said support being tiltable so as to tilt the feed box and means for tilting said support.

In witness whereof, I hereunto subscribe my name this 11th day of June, A. D., 1923.

ALONZO ALDRICH.
